BABY CARRIAGE CONSTRUCTION

Jack Glick, New York, N. Y., assignor of one-half to Benjamin Lederman, New York, N. Y.

Application November 13, 1936, Serial No. 110,631

1 Claim. (Cl. 280—47)

This invention relates to an improvement in baby carriage construction, and particularly to a means by which a clock, watch or timepiece may be mounted on a portion of the carriage to render it visible for time-telling and accessible for winding and adjustment when necessary.

As is well known, the importance of attending to the wants of an infant with punctuality cannot be overestimated. This is particularly true of feeding periods. Often a mother or nursegirl, not conscious of feeding time, inadvertently fails to feed her infant punctually. This generally occurs when the child is outdoors in its carriage and the person in charge of the child is without a timepiece.

The object of this invention therefore, is to provide a mounting for a clock or watch on a baby carriage whereby the dial or face of the timepiece will be visible to the person propelling the carriage or taking care of the infant occupant of it and will not only serve to constantly apprise the mother or nurse of the time of the day, but will make her "time-conscious" and thereby cause her to be punctual in attending to the feeding wants of the infant.

More particularly, the invention contemplates the provision of a clock or watch in the body of the carriage so mounted as to present its dial or face exteriorly of the carriage to thereby be easily visible to a person walking in the propelling position of the carriage and without disturbing the infant occupant.

In the accompanying drawing, wherein several embodiments of the invention are shown, Fig. 1 is a perspective view of a baby carriage showing the end panel of the body thereof provided with a clock; Fig. 2 is a sectional view through the upper portion of the end panel showing the clock mounting; and Fig. 3 is a perspective view showing the clock mounted in the sun vizor of the carriage.

In Fig. 1 of the drawing is shown a baby carriage of conventional construction provided with the chassis 5 on which is mounted the body 6 having an end panel 7, propelling handle 8, and a collapsible top 9 provided with a foldable sun vizor 10. All of the elements just mentioned are conventional in baby carriage construction and form no part of the invention.

In the embodiment of the invention shown in Fig. 1, the end panel 7 of the body is provided near its upper end with an aperture 11 receiving a plate or panel 12 which is hinged at 13, and provided with a knob 14 or other means by which it may be swung to an open position when desired. The plate or panel 12 forms a mounting for a clock 15 having its face or dial 16 facing the outside surface of the plate or panel 12 and in such a position that it is plainly visible to a

person standing behind the propelling handle 8 and engaged in propelling the carriage. The interior of the carriage is padded as at 17 in the usual manner and said padding is provided with a recess 18 directly behind the casing of the clock 15 to receive and accommodate the rearwardly projecting winding knobs and other adjustments for the clock as clearly shown in Fig. 2. In its usual position the clock appears as shown in Figs. 1 and 2 with only its face exposed and its rear portion accommodated in the recess 18 and covered and concealed by the padding 17. In such a position, the dial of the clock is always visible to the person propelling the carriage so that such person is thereby made "time-conscious" and will accordingly take care of the needs of the child at the proper time. To wind the clock it is merely necessary to swing the plate or panel 12 away from the body of the carriage on the hinges 13 so that the winding and setting means at the back of the clock are instantly accessible. It will also be noted that the propelling handle forms an enclosure and is therefore a means of protection for the clock face and prevents it from breakage should the carriage collide with anything.

While I have shown the clock situated in the end panel 7 of the carriage, it is obvious that it may be elsewhere located, its location being mainly dependent upon the structure of each type of carriage in which it is to be installed. It is desirable however, that the face of the clock be projected toward or visible to the nuresmaid or person propelling the carriage so that the time can always be ascertained without disturbing the occupant of the carriage. For example, in Fig. 3, the hinged or movable sun vizor 10 is shown provided with a clock 20 which may be installed directly in the sun vizor or in a separate plate 21, attached thereto. These and other modifications may be readily made without departing from the spirit of the invention.

What I claim is:

In combination, a baby carriage having a body with a rear panel and a propelling handle positioned rearwardly of the panel, the inner side of the rear panel being padded and having a recess in the padded portion opening through the rear panel, a closure plate for the recess carried by the panel and flush therewith when in closed position and a clock carried by the closure plate having the mechanism thereof normally positioned in said recess with the dial of the clock set in an opening in the closure plate and with the dial viewable at the rear side of the panel and positioned to be protected by the carriage propelling handle.

JACK GLICK.
